UNITED STATES PATENT OFFICE.

FRANK EGON NEITZEL, OF SAN FRANCISCO, CALIFORNIA, ASSIGNOR TO BETHLEHEM SHIPBUILDING CORPORATION, LTD., OF SOUTH BETHLEHEM, PENNSYLVANIA, A CORPORATION OF DELAWARE.

MULTIPLE SPINDLE DRILL.

Application filed July 31, 1919. Serial No. 314,510.

To all whom it may concern:

Be it known that I, FRANK EGON NEITZEL, a citizen of the United States, residing in the city and county of San Francisco, State of California, have invented a new and useful 5 Multiple Spindle Drill, of which the following is a specification.

My present invention comprehends a novel construction of a multiple drill which is especially designed for drilling the holes for tubes in boiler drums, although as is apparent, it can be employed in all cases where in it is desired to simultaneously drill or ream a multiplicity of holes.

It further comprehends a novel construction and arrangement of a drill head, novel means for mounting the drill heads so that they may be brought into closely spaced relationship, novel driving mechanism for the spindles carried by the drill heads and a novel construction and arrangement of mechanism for controlling the spindle driving mechanism.

It further consists of a novel construction and arrangement of actuating mechanism for the feed table which is preferably automatically controlled by means on the spindle carrying head.

Other novel features of construction and advantage will hereinafter more clearly appear in the detailed description of the invention.

For the purpose of illustrating one manner of carrying out my invention in practice, I have shown in the accompanying drawings a typical embodiment of it which in practice will give satisfactory and reliable results. It is, however, to be understood that this embodiment is typical only and that the various instrumentalities of which my invention consists can be variously arranged and organized and that the invention is not limited to the precise arrangement and organization of these instrumentalities as herein set forth.

Figure 1 represents, in front elevation, a multiple spindle drill, embodying my invention.

Figure 2 represents a top plan view of the drill.

Figure 3 represents an end elevation of the drill, viewed from the left-hand side of the machine.

Figure 4 represents an end elevation of

the drill, viewed from the right-hand side of the machine.

Figure 5 represents, in perspective, a tripping device employed and certain of its adjuncts.

Figure 6 represents, on an enlarged scale, 60 an end elevation of certain parts seen at the left-hand side of the machine.

Figure 7 represents a plan view, partly in section, of certain features of construction at the left-hand side of the machine.

Figure 8 represents a section on line 8—8 65 Figure 7.

Figure 9 represents, in perspective, and in detached position, a nut employed which is shown in assembled position in Figure 8. 70

Figure 10 represents a section on line 10—10 Figure 2.

Figure 11 represents a section on line 11—11 Figure 1.

Figure 12 represents an end elevation, 75 partly in section, of certain features of the table controlling mechanism.

Figure 13 represents a sectional view of a portion of the drum seen in Figure 12.

Figure 14 represents a top plan view of a 80 stop member seen in Figures 12 and 13.

Figure 15 represents, in sectional elevation, a bolt and the stop which it carries.

Figure 16 represents a bottom plan view 85 of the construction seen in Figure 15.

Figure 17 represents a section on line 17—17 of Figure 2, showing more particularly the manner in which the drum and certain of its adjuncts are mounted.

Figure 18 represents a section on line 18—18 Figure 19.

Figure 19 represents a section on line 19—19 of Figure 18.

Figure 20 represents a section on line 20—20 of Figure 1, showing more clearly 95 the manner in which the spindles are mounted and driven.

Figure 21 represents a section on line 21—21 Figure 1.

Figure 22 represents a section on line 100 22—22 of Figure 1.

Figure 23 represents, in sectional elevation, another embodiment of my invention wherein spacing elements are employed between the spindle sockets.

Figure 24 represents, in perspective, a spacing element seen in Figure 23.

Figure 25 represents a section on line

25—25 of Figure 1, showing more clearly, on an enlarged scale, the manner in which the drill spindles are mounted and driven.

Figure 26 represents, in front elevation, 5 the feed gear box and certain of its adjuncts.

Figure 27 represents a section on line 27—27 of Figure 26.

Figure 28 represents a section on line 28—28 of Figure 1, showing more clearly 10 the friction feed, and the manner in which it is controlled.

Figure 29 represents a section on line 29—29 of Figure 27.

Figure 30 represents a section on line 15 30—30 of Figure 29.

Figure 31 represents a section on line 31—31 of Figure 29.

Similar numerals of reference indicate 20 corresponding parts.

Referring to the drawings,

The framework of the machine.

The framework of the machine consists of a base or foundation 1 to which are connected side frames 2, braced at their upper end by means of a cross beam 3 of structural metal of any desired shape. The base 1 is provided with laterally extending tracks 4, see Figures 1 and 2, which extend outwardly 25 beyond the base and are supported at their outer ends by brackets 5 connected to the base. The tracks are adapted to have mounted on them a work carrying table 6, having the depending ribs 7, see more particularly Figure 1, which are guided in the 30 slots 8 in the track 4.

The table 6 is provided with means for actuating it, and such means will be herein-after fully set forth.

40 The base of the machine carries a main driving motor 9, see Figure 4, the shaft of which is provided with a pulley 10, around which passes a belt 11, which also passes around a compound pulley 12 which is 45 mounted on a countershaft 13 journaled in the side frames.

14 is a belt which passes around the pulley 12 and also around a compound pulley 15 mounted on a shaft 16 carried by a side 50 frame 2. A belt 17 passes around the pulley 15 and around a pulley 18 mounted on a shaft 19 which also has mounted on it a pulley 20, around which passes a belt 21, which also passes around a pulley 22, mounted on 55 a shaft 23 journaled in the machine framework.

The feed gear box.

The shaft 23 extends into the feed gear 60 box 24 which is carried by the cross beam 3, which connects the side frames 2. The shaft 23 is provided with a pinion 25, see Figure 29, which meshes with a gear 26, the hub of which is loosely mounted on a 65 shaft 27 journaled in the gear box.

The shaft 23 is also provided with a worm 28 which meshes with a worm wheel 29, see Figure 30, mounted on a shaft 30, which latter also has mounted on it a worm 31, which meshes with a worm wheel 32, the hub of which is loosely mounted on the shaft 27. The hub of the gear 26 is provided 70 with a clutch face 33, which co-operates with a clutch collar 34 of a clutch collar 35, which latter is also provided with a clutch face 36, which co-operates with a clutch face 37 of the worm wheel 32, so that the shafts 23 and 27 can be operatively connected with each other.

The clutch collar 35 is keyed to the shaft 80 27 to rotate in unison with it and the clutch collar 35 is provided with a yoke 38, which is fulcrumed at 39 and has an arm 40, which extends through a slot in the gear box 24 and has its outer end extending into a slot 41 in a longitudinally slid able rod 42, which is loosely mounted on the gear box.

The rod 42 has fixed to it a rack sleeve 43, see Figure 28, with which engages a rack segment 44 fixed to a rock shaft 45 journaled on the feed gear box 24. An actuating arm 46 is fixedly secured to the forward end of the rock shaft 45. The rock shaft 45 has loosely mounted on it an actuating lever 47 to which is connected one end of a slide bar 48 guided in a sleeve 49 on the feed gear box 24, see Figures 1 and 26.

The bar 48 is provided with an inclined or bevelled face 50, see more particularly Figure 26, which merges into a straight face 51, and the free end of the slide bar 48 is provided with a downwardly extending lug 52.

53 designates a roller which normally engages the straight face 51, and this roller is carried by a spring-pressed plunger 54, which is keyed in a bracket 55 so as to have only longitudinal movement, and a spring 56 is provided which tends to retain a stop arm 57 on the plunger in its upward or operative position and in the path of an arm 58 which extends through a slot 59 in the feed gear box and is connected to the yoke 38, see more particularly Figure 30.

I provide a friction brake for such yoke 38, which consists of a plunger 60, see more particularly Figure 30, slidable in a sleeve 61 extending through a wall of the feed gear box 24. A spring 62 is provided one end of which abuts against the plunger while its opposite end abuts against an adjusting screw 63 in engagement with the sleeve and provided with a lock nut 64. The plunger bears against a roller 65 carried by the yoke 38.

The shaft 23, see Figures 26, 28 and 29, has mounted on it a friction gear 66, and the shaft 27 has mounted on it a friction gear 67.

As will be best understood by reference to Figure 28, a rock shaft 68 is suitably

journalled on the feed box 24 and in a bracket 69, and is provided with a rock arm 70, the outer end of which carries a friction gear 71, which is adapted to be brought into operative engagement with the friction gears 66 and 67 by means of a lever 72, one end of which is fixed to the rock arm 68. The front end of the arm 72 extends in front of the machine as seen in Figure 1, and is provided with a manually actuated cable 73. The arm 72, see Figure 28, is maintained in its inoperative position by means of a spring 74, one end of which is connected to the arm 72, while its opposite end bears against a suitable fixed point such as for example the cross beam 3.

The shaft 27, see Figures 1 to 4 inclusive, and Figure 20, is provided at each end with a gear 75, which meshes with a gear 76 fixed to a vertically disposed feed screw 77, provided with a collar 78 mounted between ball bearings 79, which are carried by a side frame 2.

The feed screws 77 pass through nuts 80, see Figures 20 and 21, which are secured by means of fastening devices 81 to a cross rail 82 which is vertically reciprocable and is recessed as at 83, see Figure 21, to receive the guides 84 extending from the side frames 2. The plates 85 are connected to the cross rail 82 by means of bolts 86 so that the cross rail 82 is properly guided in its upward and downward movements.

87 designates a spindle carrying head or drill support, which is mounted in a keyway or guide 88 on the cross rail 82, and in order to provide for the lateral adjustment of the drill head support 87 an adjusting screw 89 is provided, which is in threaded engagement with a nut 90 which is fixed to the drill head support 87, see Figure 22.

Mechanism for laterally adjusting the spindle carrying head.

45 The free end of the adjusting screw 89 is provided with a grasping handle 91, see Figures 1 and 4, by means of which it may be rotated, it being seen from Figure 21 that the adjusting screw 89 is provided with set collars 92 located on opposite sides of the portion in which it is journalled to prevent longitudinal movement of the adjusting screw 89 with respect to the cross rail 82.

The drill heads and their spindles.

93 designates the spindles, rotatably mounted in their respective drill heads 94 or 100, see Figures 20 and 25, antifriction thrust bearings 95 being positioned between each spindle and its drill head. Certain of the drill spindles 93 have at their upper ends the gears 96 which are retained in position by the nuts 97. The gears 96 mesh with the spiral gear 98 journalled in the rearwardly extending brackets 99 of the drill head 94.

The drill heads 100 are of the same construction as the drill heads 94 except that the offset brackets 101 extend forwardly instead of rearwardly. The spindles 93 of the drill heads 100 are provided with gears 102 which mesh with a driving gear 103 journalled in the brackets 101. The drill heads are fixed in their adjusted position by means of set screws 104. The gears 98 and 103 are journalled in brackets carried by the cross rail 82, see Figures 1 and 2. The spindle driving gear 103 has fixed to it a gear 105 which meshes with a gear 106 on the driving gear 98. The driving gear 103 is journalled in brackets 107 and is provided with pulleys 108 around one of which passes the belt 17 which also passes around idlers 109 carried on the cross rail 82 so that a uniform arc of contact for the belt is maintained on the driving pulley for the drill spindles.

A driving belt 110 at the opposite end of the machine passes around the other spindle driving pulley 108 and around idlers 111, carried by the cross rail 82, and also around pulleys 112 and 113, the pulley 112 being carried by a stud shaft 111 and the pulley 113 being mounted on a shaft 115 extending from a side frame 2. The pulley 113 is a compound pulley and has passing around it a belt 116 which also passes around a pulley 117 mounted on the countershaft 13, see Figure 3, which latter as before explained is driven from the main driving motor 9, see Figure 4.

The side frames 2 are provided with brackets 118 which carry sheaves 119 over which pass cables 120 connected to the cross rail 82 and to counterbalance weights 121, see Figures 2, 3 and 25.

The drill heads 94 and 100 are apertured to receive a laterally extending rod 122, see Figures 1, 20, 23 and 25, which is secured in fixed position by means of set screws 123. Spacing members 124, see Figure 24, which are preferably U-shaped, are placed on the rod 122 between adjacent drill heads. One end of the rod 122 is headed and the other end is provided with threads to receive the nuts 125, one of which serves as a lock nut.

Actuating means for the work table.

The shaft 115, see Figures 2, 3, 6, 7 and 10, is continuously running and carries a spiral pinion 126 always in mesh with a spiral gear 127 loosely mounted on a shaft 128, see Figure 10, which at its rear end is provided with a spiral pinion 129 engaging a spiral gear 130 fixed to a shaft 131, see Figure 2. This shaft 131 has on it bevel gears 132 meshing with bevel gears 133 on the worm shafts 134 journalled on the base 1 and engaging nuts 135 carried by the work table, see Figure 11.

In order to provide a quick return of the work table, I employ a motor 136, the shaft 130

of which has a gear 137 in mesh with a gear 138 fixed to a shaft 139 suitably journalled and provided with a clutch collar 140, the clutch face of which engages with a clutch member 141 fixed to the shaft 128, such engagement being controlled by means of a manually actuated clutch lever 142, see Figures 1, 2, 3, 7 and 10.

The hub of the gear 127 has fixed to it a clutch member 170, see more particularly Figures 7 and 10, keyed to the shaft 128 and adapted to be engaged by a clutch collar 143 against which bears one end of a spring 144, the other end of which bears against a set collar 145 adjustable on the shaft 128. The clutch collar 143 has a clutch arm 210 extending laterally from it and connected to a longitudinally slidabie shifter rod 146 mounted in standards 147 and having a threaded portion 148, see Figure 8, on which is adjustably secured by means of nuts 149 a rod shifting member 150, see also Figure 9. The member 150 is provided with a cam shaped lug 151. The free end of the shifting rod is faced off or bevelled, as at 152. The free end of the rod 146 is engaged by a tripping device which will now be described, see Figures 18 and 19. A stand 153 has a vertically disposed aperture 154 through it which is of reduced diameter at 155 to limit the upward movement of a block 156 connected to a trigger 157 which is normally held in its raised position by means of a spring 158 and is keyed to the stand.

The trigger has an apertured head 159 in which is mounted a latch 160 having a longitudinal groove 161 into which extends a screw 162 to prevent rotation of the latch. The latch has a reduced portion extending through the rear end of the trigger head and provided with a nut 163. A spring 164 is interposed between a portion of the latch and the trigger head to normally retain the latch in its forward position.

The trigger head has fixed to it a ring 165 having a laterally extending toe 166 positioned beneath the operative end of the latch 160 and having its top face bevelled. The stand 153 is apertured as at 167 to receive the rounded end of a rock arm 168 which extends through an aperture 169 in the block 156. The rock arm 168 has its rear end connected to a rock shaft 171, see more particularly Figures 7 and 12, journalled in standards 172. The rock shaft 171 has a rock arm 173 connected to one end of a longitudinally adjustable rod 174 pivotally connected at 175 to a lever 176 one end of which is pivotally supported at 177 on a side frame 2, while the other end of such lever is connected at 178 to a bar 179, see Figure 3, which latter is pivoted at its upper end to one end of a link 180. The other end of the link 180 is pivotally supported on the side frame 2.

The bar 179 carries a thrust member 181 having its top face bevelled, see Figures 3, 5 and 12, and the member 181 is in the path of a latch or trip member 182 carried by the cross rail 82 and having a cam face 183. The shifting rod 146 travels on a suitably supported roller 184.

The shaft 128 has mounted on it a worm 185 which meshes with a worm gear 186 keyed to a shaft 187 suitably journalled above the base 1. The shaft 187 has keyed to it a threaded sleeve 188, see Figure 17, which moves longitudinally in a fixed nut 189. Fixed to the sleeve 188 is a drum 190 having in its periphery spiral T-shaped grooves 191 forming a coarse pitch screw to receive the rectangular shaped heads 192 of the threaded studs 193, see Figures 13, 14, 15 and 16.

These studs receive the nuts 194 which secure them in adjusted position on the drum and form stops. The nuts 194 are grooved as at 195 to receive a suitable tool for securing them in position. Belt tighteners 196 and 197 are provided for the belts 110 and 116, respectively, see Figure 3. Belt tighteners 198 and 199 are provided for the belts 14 and 17, respectively, see Figure 4. 200 is a valve controlled apertured pipe supported by hangers 201 from the head 87, see Figure 1, and leading from a source of fluid supply (not shown). The spindles 93 carry the working tools 202 such as for example, the drills shown in the drawings.

The clutch lever 142, see Figure 6, has connected to its lower end, as at 203, one end of a link 204, the other end of which is connected to a rod 205. The other end of the rod 205 is provided with a slot 206 into which extends a pin 207 supported at one end of a lever 208 which is fulcrumed at 209 and has its opposite end connected to the clutch collar 143 so that the clutch may be thrown out when desired and a direct connection effected between the auxiliary motor 136 and the shaft 128 which is operatively connected to the work table to actuate it.

The operation.

The operation of my novel construction of multiple drill will now be readily apparent to those skilled in this art and is as follows:—

The drill heads 94 and 100 are assembled in the desired spaced relation on the spindle carrying head 87 and the spacers 124 placed in position after which the nuts 125 are tightened, see Figures 1 and 23. The stops 194 are secured in their proper position on the drum 190, see Figure 13, so that the work table will be intermittently actuated. Assuming now that the work, such as for example, a boiler drum, has been clamped in position on the work table 6, the operator if he desires a rapid feed draws downwardly

on the cable 73 thereby rocking the shaft 68, see Figures 28 and 26, and causing the friction gear 71 to engage the friction gears 66 and 67, see more particularly Figure 29. 5 This causes the shaft 27 to rotate the feed screws 77 which are intergeared with it, as will be understood by reference to Figures 1, 2 and 20. As the feed screws 77 mesh with the nuts 80 carried by the cross rail 82, the 10 cross rail 82 and its adjuncts will be raised or lowered depending upon the direction of rotation of the feed screws 77 and as described the operation of the cable 73 will cause the cross rail 82 to be fed downwardly 15 to effect the drilling or other operation which is to be performed.

In the usual operation of drilling, as soon as the drills are brought into proper position with respect to the work, the operator 20 actuates the lever 47 to rock the shaft 45 and cause the gear segment 44 to move the bar 42 in the proper direction to effect the rotation of the shaft 47 in one direction or the other, it being remembered that the shaft 25 47 is operatively connected to the feed screw to effect the raising and lowering of the head on which the drill heads are mounted. If the slide rod 42, see Figure 29, is moved to the left, the clutch member 34 will engage 30 the clutch member 33 and if the rod 42 is moved in a reverse direction, the clutch member 36 will engage the clutch member 37, see Figure 31. By such construction the shaft 23, which is operatively connected to 35 the main driving motor 9 to be continuously driven thereby, can be operatively connected with the shaft 27 to rotate it in one direction or the other and thereby effect the raising or lowering of the cross head 82 on which 40 is supported the spindle carrying head 87 to which the drill heads are connected.

It will be understood that during the operation of the machine the main driving motor 9 causes the countershaft 13 to revolve and as this countershaft 13 is operatively connected by means of suitable belts and pulleys with the shaft of the spiral gear 103 such gear 103 is continuously revolved. This gear 103, see Figure 2, is intergeared 45 with the spiral gear 98 so that the revolution of all of the drill spindles is effected, as will be understood by reference to Figures 1, 2, 3 and more particularly Figures 20 and 25.

Where the spacing of the holes across the 50 work is less than the minimum spacing of the drill spindles, the side movement of all the spindles is obtained by actuating the handle 91, see Figures 2, 21 and 22, thereby rotating the feed screw 89 and effecting the 55 lateral adjustment of the spindle carrying head 87. The drill spindles may be spaced to suit any particular holes by shifting them along the cross rail formed by the spindle carrying head and clamping them in their 60 adjusted position by means of the clamping

screws 104, see more particularly Figure 25. By employing an inner and an outer spiral gear, such as 98 and 103, respectively, to drive the drill spindles, I am enabled to space the spindles much more closely together than would be possible if a single driving gear was employed for all of the 70 spindles.

In order to prevent improper movement or accidental displacement of the yoke 38 from the position to which it has been moved, I provide a stop member or arm 57, see Figures 26 and 30, and a friction brake 60, see Figure 30, which latter bears against a roller 65. The stop arm 57 is normally 80 maintained in its raised position by means of the spring 56, see Figure 26. When the handle 47 is actuated to move the slide bar 48 to the left, the cam face 50, see Figure 26, acting on the roller 53, draws downwardly the spring pressed plunger 54 and moves the stop arm 57 out of the path of the arm 58 which is connected to the yoke 38, see Figure 30, of the clutch mechanism which controls the operation of the clutch collar 90 35 which is keyed to the shaft 27.

The operation of the table feeding mechanism.

Referring now more particularly to Figures 1, 2, 3, and 5 to 19 inclusive, I will describe in detail the manner in which the feed of the work table 6 is effected. The cross rail 82 carries a latch or trip member 182 which moves in the path of a thrust member 181 secured to the bar 179, see more particularly Figures 3, 5, 6 and 12. When the cross head 82 reaches the limit of its downward travel and the drilling operation is completed, the operator by actuating the 100 arm or handle 46 operates the yoke 38 in the feed gear box to cause the drill heads and their spindles to move upwardly as will be understood from the foregoing description.

The cross head 82, see more particularly Figure 5, is provided with a latch 182, which travels in the path of the thrust member 181 secured to the bar 179, so that as the drill spindles and their adjuncts are moved upwardly, the bar 179 will be raised thereby rocking the free end of the lever 176 upwardly, see Figure 6, and causing the rod 174 to rock the shaft 171 and causes the rock arm 168, see Figures 12, 18 and 19, to move downwardly, thereby drawing downwardly the plunger 157 against the tension of the spring 158. This movement of the plunger 157 bends the latch end of the shifting rod 146 downwardly, see more particularly Figures 7 and 8, thereby moving the cam shaped lug 151 out of the path of a stop 194 on the drum 190.

As soon as the lug 151 is drawn downwardly out of the path of the stop 194, the 130

compression spring 144, see Figure 7, causes the clutch member of the clutch collar 143 to engage the clutch member 142 of the gear 127 which is loosely mounted on the shaft 128, see more particularly Figure 10. This gear 127 as before explained is continuously revolved by the gear pinion 126 so that as soon as the clutch is closed in the manner described, the shaft 128 begins to revolve thereby causing the gear 129 to rotate the gear 130 on the shaft 131 and as this shaft 131 is intergeared with the feed screws 134 which as best seen in Figure 11 passes through feed nuts carried by the work table 6, the work table is moved into its next position.

The shaft 128 has fixed to it the worm 185 which drives the worm gear 186 and thereby the shaft 187 see more particularly Figures 10, 12 and 17. This shaft 187 is keyed to the sleeve 188 which works in a fixed nut 189, so that a lateral movement of the drum 190 is effected during its revolution.

As soon as the next stop 194 on the drum 190 comes into the path of the lug 151 on the shifting rod 146, see Figure 8, it engages such lug and moves the shifting rod 146 rearwardly or to the left of the position seen in Figure 7 and brings its free end into position so that the trigger 157 will retain such free end in its raised position with the lug 151 in engagement with the stop 194. The spring pressed latch 160 passes by the end of the shifting rod and the flange 166 carried by the trigger 157 prevents the downward movement of the free end of the piston rod until it is again tripped, it being understood that at this time the spring 158 is holding the trigger 157 in its raised position. The shifting rod 146 in its rearward movement moves the clutch collar 143 into its inoperative position so that there is no operative connection at this time between the gear 127 and the shaft 128. The feed of the table is thus stopped until the shifting rod is again tripped in the manner before described.

If a quick return of the work table 6 to its forward position is desired, the handle 142 is actuated thereby throwing in the clutch collar 140, so that the auxiliary motor 146 is directly connected with the shaft 128. This lever 142 is also connected with the clutch collar 143, see Figures 3 and 6, so that such clutch collar 143 is actuated at the same time. The pin and slot connection 207 and 206 permits the proper actuation of the clutch collar 143 when the shifting rod is tripped automatically by the upward movement of the cross head 82. It will be seen from Figure 5 that the top face of the thrust member 181 is bevelled and the latch 183 is provided with a cam face on its under side so that it can pass by the thrust mem-

ber 181 as the cross head 82 moves downwardly during the drilling operation.

It will be apparent that in accordance with my present invention the drills or other working tools can be adjusted to conform to any desired lay out of the holes on the work either by inserting or removing certain of the drills, by adjusting the position of the drill head or by lateral movement of the drill head support or cross rail 87.

It will now be apparent that I have devised a novel and useful construction of a multiple spindle drill which embodies the features of advantage enumerated as desirable in the statement of the invention and the above description, and while I have, in the present instance, shown and described a preferred embodiment thereof which will be found in practice to give satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent, is:—

1. In a multiple spindle drill, a cross head, means to raise and lower it, a drill head support guided in said cross head, means to laterally adjust said support, drill heads movable on said support, means to clamp each drill head in its adjusted position, drill spindles for said drill head, a rod passing through said drill heads, clamping means on each drill head to engage said rod, and means to drive said drill spindles.

2. In a multiple spindle drill, a cross head, means to raise and lower it, a drill head support guided in said cross head, means to laterally adjust said support, drill heads movable on said support, means to clamp each drill head in its adjusted position, drill spindles for said drill head, a rod passing through said drill heads, clamping means on each drill head to engage said rod, means to drive said drill spindles, and means co-operating with said rod to maintain said drill heads in fixed relation with respect to each other.

3. In a multiple spindle drill, a cross head, means to raise and lower it, a drill head support adjustable on said cross head, drill heads on said support, a rod passing through said drill heads and adjustably connected thereto, U-shaped spacers on said rod between juxtaposed drill heads, means to bodily move said drill head support to simultaneously adjust all of said drill heads, drill spindles carried by said drill support, and actuating means for said drill spindles.

4. In a multiple spindle drill, a continuously driven shaft, a second shaft, clutch

mechanism operatively connecting said shafts and including a friction drive and reversing mechanism, means to actuate said clutch mechanism to drive the second shaft 5 in a clockwise or a counterclockwise direction, manually controlled means to render said friction drive operative, spaced feed screws driven by said second shaft, a cross head operatively connected with said feed 10 screws to be raised and lowered by them, drill spindles operatively connected with said cross head, and means to continuously drive said drill spindles.

5. In a multiple spindle drill, a continuously driven shaft, a second shaft, clutch mechanism operatively connecting said shafts and including a friction drive and reversing mechanism, means to actuate said clutch mechanism to drive the second shaft 15 in a clockwise or a counterclockwise direction, manually controlled means to render said friction drive operative, manually actuated means to lock said clutch mechanism in its adjusted position, feed screws inter- 20 geared with said second shaft, a cross head operatively connected with said feed screws to be raised and lowered by them, drill spindles operatively connected with said cross head, and means to continuously drive said 25 drill spindles.

30 6. In a multiple spindle drill, a continuously driven shaft, a second shaft, clutch mechanism operatively connecting said

shafts and including a friction drive and reversing mechanism, means to actuate said clutch mechanism to drive the second shaft 35 in a clockwise or a counterclockwise direction, manually controlled means to render said friction drive operative, a friction brake for said clutch mechanism, feed screws inter- 40 geared with said second shaft, a cross head operatively connected with said feed screws to be raised and lowered by them, drill spindles operatively connected with said cross head, and means to continuously drive said 45 drill spindles.

7. In a multiple spindle drill, a driven shaft, a second shaft, clutch mechanism operatively connecting said shafts and including a clutch operating member, a cross head actuated by said second shaft, drill spindles operatively connected with said cross head to be supported thereby, actuating means for 50 said drill spindles, a spring actuated stop in the path of said clutch operating member, manually controlled means to effect the release of said stop, a slide rod operatively connected with said clutch operating member and provided with a rack, a rack segment engaging said rack, and a manually controlled rock shaft operatively connected 55 with said rack segment to actuate it.
